UNITED STATES PATENT OFFICE.

GEORGE O. CURME, JR., OF PITTSBURGH, PENNSYLVANIA, ASSIGNOR TO CARBIDE & CARBON CHEMICALS CORPORATION, A CORPORATION OF NEW YORK.

PROCESS OF CHLORINATING GASEOUS HYDROCARBONS AND RECOVERING PRODUCTS THEREFROM.

1,422,838.

Specification of Letters Patent.

Patented July 18, 1922.

No Drawing.

Application filed July 7, 1920. Serial No. 394,571.

To all whom it may concern:

Be it known that I, GEORGE O. CURME, Jr., a citizen of the United States, residing at Pittsburgh, in the county of Allegheny and 5 State of Pennsylvania, have invented certain new and useful Improvements in Processes of Chlorinating Gaseous Hydrocarbons and Recovering Products Therefrom, of which the following is a specification.

10 This invention relates to the chlorination of such hydrocarbons as yield substitution products with chlorin or equivalent halogens when treated therewith in gaseous phrase; and to the separation and recovery of the 15 reaction products, including the halogen acid.

An essential feature of my invention consists in effecting the chlorination of the hydrocarbons in the gaseous phase and under 20 anhydrous conditions, and thereafter isolating from the reaction mixture the unchanged hydrocarbon, the chlorin derivatives thereof, and the halogen acid, or some of them, by liquefaction methods comparable to 25 those applicable for the separation and recovery of the components of air or other mixtures of so-called fixed gases. By proceeding in this way certain highly important technical advantages are secured as hereinafter explained. I will explain my process 30 by reference to methane as a typical gaseous hydrocarbon yielding substitution products with chlorin; although it is to be clearly understood that the process is applicable broadly to the halogenation in gaseous 35 phase of all hydrocarbon bodies of the nature above indicated. For example ethane may be treated in substantially the same manner, although the products thereby obtained have at the present time a decidedly 40 lower industrial value.

In this connection it may be explained that the general procedure of chlorinating methane, or gases rich in methane, is one 45 which has been carried out by many independent investigators under a great variety of operating conditions. It has been thoroughly demonstrated that the four following reactions may be made to proceed

smoothly with the absence of the explosive 50 side reactions:—

Also, by proper control of the proportion of chlorin used, any of the desired reactions may be made to predominate, although in no case, with the possible exception of the 60 formation of carbon tetrachlorid, does any single reaction proceed to the exclusion of all others; for in every case certain quantities of all the other theoretically possible products are formed. In case carbon tetrachlorid is the desired product a practically theoretical yield may be obtained by using a sufficient excess of chlorin. In case any of the other derivatives is desired, more care must be observed in choosing the quantity 65 of chlorin and also in controlling the other conditions of the reaction. It is further to be noted that ethane or higher paraffins are much more easily attacked by chlorin than is methane; and accordingly an 70 extensive waste of chlorin is caused by the presence of substantial proportions of these higher paraffins, which yield per-chlorinated derivatives of little or no present industrial value, together of course with the 75 equivalent quantities of hydrochloric acid.

An examination of the equations (1) to 80 (4) above shows that hydrochloric acid is one of the principal products of the reaction; and in order to operate economically 85 this material must be recovered. By the usual procedure this involves the rather difficult absorption in water, and results in the introduction of moisture into the gas mixture, which is thereby rendered unfit for 90 direct re-use in the chlorinating process. Also, the methyl chlorid, being a very volatile substance (boiling point—24° C.) is very difficultly condensed from the large excess of methane, even after the removal of the 95 hydrochloric acid; and is therefore either partly wasted, or is returned to the system and undergoes chlorination to a higher

- stage. Under present commercial conditions, with an acute shortage of methyl alcohol and its derivatives, it is chiefly the lighter chlorinated derivatives of methane which are desired. Accordingly a high yield and good recovery of methyl chlorid and of methylene chlorid are the principal desiderata in the successful operation of the present process.
- 10 The present invention affords a minimum production of undesirable material, a maximum utilization of the chlorin, and a practically complete recovery of all of the products of reaction in a condition for easy commercial utilization.
- 15 A preferred embodiment of the invention is as follows:
- Substantially pure methane is first isolated from any available gas mixture, such as natural gas or any of the various industrial gas mixtures. This may be accomplished by a process essentially the same in principle as that now widely employed for the separation and recovery of nitrogen, 20 oxygen, argon, etc. from atmospheric air; that is to say by liquefaction and rectification, preferably in columns of the Linde type. The methane is then mixed with suitable proportions, say 5 to 30% more or less, 25 of chlorin, the proportion varying according to the predominating product desired: and the mixture is passed at elevated temperatures over any suitable catalytic material, which in the preferred embodiment of 30 the invention is so-called "activated carbon" prepared by the Chaney process. All materials entering into the reaction as well as the catalyst, should be moisture-free, under which conditions the entire operation, including the steps later to be described, may 35 be carried out in iron or steel apparatus. It will be understood however that my invention is not restricted to any specific operating conditions during the chlorinating 40 step.
- 45 In the preferred embodiment of the process the operation will be cyclical in character, in the sense that methane, substantially undiluted by nitrogen or other gases, will be repeatedly circulated through the system including the catalyzer; the chlorinated products including the hydrochloric acid being substantially separated from the gas mixture at each repetition of the cycle.
- 50 For this purpose dry methane and dry chlorin are constantly supplied to the reacting system in the desired proportions, these gases, with a large excess of methane, being then continuously circulated through the catalytic chamber; thence through a water-cooled condenser where heavier reaction products such as chloroform and carbon tetrachlorid are partly condensed; then compressed to several atmospheres pressure, and 55 led through a heat exchanger into a liquefaction and rectification tower, preferably of the Linde type. In this tower the temperature is such that substantially all of the substances present with the exception of the methane (together with any nitrogen or air 60 which may be incidentally present as impurities) are condensed and retained as a liquid mixture, the excess methane alone being carried in gaseous phase through the heat exchanger and used again in the same 65 operating cycle. This procedure is made possible by the extremely low boiling point of methane (-165° C.) which is materially lower than that of any other component of the original reaction mixture. Small quantities of hydrochloric acid (boiling point -80° C.) may carry through with the methane in gaseous form, but this is generally unobjectionable, since the concentration is not large and cannot build up beyond a small 70 equilibrium point.
- 75 The exact method of producing and maintaining this low temperature in the liquefaction and rectification tower is not material to the present invention, since several methods will readily suggest themselves to those skilled in this art, the Linde system being preferred.
- 80 The liquid mixture retained contains the following substances in varying proportions, 85 to wit:—
	Boiling point.
Hydrochloric acid	-80° C.
Methyl chlorid	-24° C.
Methylene chlorid	$+42^{\circ}$ C.
Chloroform	$+61^{\circ}$ C.
Carbon tetrachlorid	$+78^{\circ}$ C.
traces only.	
- 90
- 95
- 100
- 105
- 110
- 115
- 120
- 125
- 130
- This mixture may then be subjected to fractional separation and rectification in any usual apparatus provided for the purpose, to obtain each component in a pure state; or the mixture may be allowed to evaporate, the vapors being led through water, and the (now concentrated) hydrochloric acid absorbed to form commercial muriatic acid. The residual chlorinated hydrocarbons may then be collected and separated in any desired manner to recover each in a state of purity. The first of these procedures is now regarded as the more desirable, since it offers the possibility of producing liquid anhydrous hydrochloric acid, capable of being stored in steel cylinders, as a new article of commerce.
- Both procedures present the great technical advantage that no moisture is brought into contact with the methane at any stage of the process, whereby as explained above, the cyclical repetition of the process in iron or steel apparatus is rendered possible.
- It is to be understood that the process as described above is likewise applicable to the preparation of halogen compounds other than chlorin compounds, for example the

corresponding bromine compounds may be thus prepared: and that therefore the other halogens are to be regarded as the equivalents of chlorin for the purposes of this invention.

5 I claim:—

10 1. Process of preparing and recovering halogen substitution-products from gaseous hydrocarbons, comprising mixing the hydrocarbon in excess with the gaseous halogen; effecting combination of the halogen with liberation of the anhydrous halogen acid;

separating the reaction products of higher boiling point than the hydrocarbon from the resulting gas mixture by anhydrous liquefaction; and returning the residual gaseous hydrocarbon to the operating cycle.

15 2. Process according to claim 1, wherein the resulting halogen products are fractionally separated from each other.

20 In testimony whereof, I affix my signature.

GEORGE O. CURME, JR.
